UNITED STATES PATENT OFFICE.

SAMUEL FISHER, OF BALTIMORE, MARYLAND.

STEAM CLOTH-SPONGING MACHINE.

Application filed February 24, 1923. Serial No. 620,992.

To all whom it may concern:

Be it known that I, SAMUEL FISHER, a citizen of the United States, residing at Baltimore, in the county of Baltimore City and State of Maryland, have invented new and useful Improvements in Steam Cloth-Sponging Machines, of which the following is a specification.

My present invention has reference to an apparatus for sponging cloth for the shrinking thereof preparatory to the making of clothing therefrom.

The primary object is to simplify and improve the existing art by producing an apparatus for this purpose which shall be characteristic of simplicity in construction, coupled with thorough efficiency in operation, and wherein a revoluble apertured drum having a fabric facing is arranged above the table and upon which the bolt of cloth rests and over which the cloth is drawn in the sponging process, means being provided for feeding comparatively dry steam into the drum, and means being further provided for further drying the steam in its passage through the apertures of the drum whereby the cloth is effectively sponged without liability of danger thereto.

The invention further resides in other features of construction and the combination and operative arrangement of elements to be hereinafter fully described, illustrated in the accompanying drawings and specifically pointed out in the appended claims.

In describing the invention in detail, reference is to be had to the drawings wherein like characters denote like or corresponding parts throughout the several views, and in which:

Figure 1 is a side elevation of the improvement, with parts broken away and parts in section.

Figure 2 is an end view thereof.

Figure 3 is a sectional view on the line 3-3 of Figure 1.

Figure 4 is a fragmentary horizontal sectional view on the line 4-4 of Figure 1.

Figure 5 is an enlarged vertical longitudinal sectional view through the steam inlet end of the drum.

Figure 6 is an enlarged sectional view approximately on the line 6-6 of Figure 2.

Figure 7 is a central longitudinal sectional view through the casing and core of the

steam inlet cock for the heating coil in the 55 rotary drum.

Figure 8 is a plan view of the burners, with parts broken away and parts in section.

As disclosed by the drawings, I make use 60 of a stand or table whose top 1 is supported on corner uprights. The uprights are in the nature of pipe sections, the front uprights 2 being of less length than the rear uprights 3, the corners of the top 1 being 65 notched for the passage of the uprights 3 thereabove. All of the uprights are connected to the under face of the top in any desired or preferred manner, such for instance as through the medium of flanged 70 collars screwed on the uprights and having screws or the like passing through the flanges thereof to enter the top. The uprights, below the top 1 have screwed in the sections constituting the same couplings 4 for the 75 reception of longitudinal pipe members 5 and transverse pipe brace members 6.

Above the top 1 there is arranged for slideable movement on the rear uprights 2 split sleeves 7 having their ends formed with outstanding ears through which are passed binding means 8, whereby the sleeves may be retained adjusted on the uprights. The sleeves have their confronting faces provided with trunnions or bearings for trunnions on the ends of a roller 9. Hingedly secured to the rear end of the table top 1, as at 10, there is a drop shelf 11. This shelf may be sustained in horizontal alignment with the top proper through the medium of 85 rods 12 that are received in suitable bearings 13 on the under face of the top 1, the outer ends of the rods being offset to provide handles 14.

A cylindrical steam generating tank 15 is 95 arranged longitudinally below the top 1. The tank has its closed ends provided with hangers 16 whose hooked ends are arranged around the transverse brace members 6 of the table frame. Each of the transverse 100 brace members comprises sections which are centrally connected by T-couplings 17, and to the vertical depending branches of these couplings there are secured short pipe sections 18 and 19 respectively. The pipe section 18 has on its lower end a collar 20 to receive therethrough the outer or front apertured burner pipe 21. The pipe section 19

has screwed on its lower end a coupling 22 that receives the second end of the burner tube 21 therethrough. The couplings 20 and 21 have smooth bores, and the end of the burner received through the coupling 22 is non-apertured, being really in the nature of a short pipe section 23 secured to the apertured burner pipe by a T-coupling 24. To the lateral branch of the T-coupling 24 there is secured a pipe section 25 that has its bore plugged, as at 26, the outer end of the pipe 25 having screwed thereon a coupling 27 that has also screwed therein one end of the second apertured burner pipe or tube 28. Both of the burner tubes have adjustably secured on their free ends castings which provide air mixing chambers 28' and 29' respectively, the same receiving therethrough the nipple ends of cocks 30 secured to a gas manifold 31 connected by a pipe 32 to the house supply. Screwed in the end of the short pipe section 23 there is a head plug 33 which, contacting with the outer end of the coupling 22 draws on the burner pipe or tube 21 to bring the air mixing chamber 28' thereof into contact with the coupling 20 of the frame pipe 18 to thus hold the burner rigidly supported by the frame.

The rear uprights 3 of the frame are, of course, of an equal length and each has secured on its upper end T-couplings 33 and 34 respectively. The longitudinal bore of these couplings is smooth, and the coupling 33 provides a bearing for the straight ends 35 of a coiled pipe 36 that is arranged longitudinally through a drum 37, the straight end 35 of the said coil 36 being welded or otherwise secured to one end of the said drum, the second end of the coil having a straight extension that passes through the second end of the drum and has screwed or otherwise secured thereon a cock 38 arranged exteriorly of the drum.

The straight end 35 of the coil 36 is provided with exterior threads and has a flared mouth. In this mouth is received the conical end of a bushing 39. The bushing has its outer face provided with a central interiorly threaded annular extension whose bore communicates with that of the bushing.

Screwed on the threaded end of the straight extension 35 of the coil 36 there is a sleeve 41 having its outer end flanged inwardly, as at 42 to surround the portion 40 of the bushing 39 and to likewise contact with the bushing proper to cause a tight frictional engagement between the conical end of the bushing and the flared mouth of the straight end 35 of the coil.

The steam branch pipe between the steam generating chamber and the coil 36 is broadly indicated by the numeral 43, the upright branch of which having its passage controlled by a manually operated valve 44,

and the valve casing has screwed in its upper end the casing 45 for a cock of a particular and peculiar construction. To the upper end of the cock casing 45 there is threadedly secured the casing 46 for a safety valve. The valve in the casing 46, indicated by the numeral 47 is held seated by a spring 48, and in the outer end of the said casing there is screwed a nipple 49 having a reduced inner end to receive therearound the upper convolution of the spring 48, the lower convolution being received around the lug on the outer face of the valve 47.

The spring is so adjusted that the valve 47 will unseat when steam between the generator tank and the coil attains a predetermined pressure.

The bore in the casing 45 for the cock plug is flared inwardly from its outer to its inner end to receive therethrough the frustoconical core 50. The core has secured on its outer closed end a crank handle 51 and is provided with a plurality of circumferentially arranged radially disposed series of restricted ports or openings 52 that communicate with its bore 53, the said apertures or openings being aligned with the vertical branch of the casing 45 and consequently being in a line with the bore of the safety valve casing 46. The core 50 is provided with a reduced extension formed at its ends with exterior threads, the outer threads being screwed in the neck portion 40 of the bushing 39, and the inner threads being engaged by a nut 53' for compressing a washer 54 against the reduced end of the lateral core receiving branch of the casing 45. By this arrangement it will be noted that the turning of the crank handle 51 will likewise turn the core 50, causing the latter to impart a rotary motion to the coil 36 and to the drum 37 that is fixed on the coil. Of course, suitable packings may be arranged between the ends of the drum and the means on which it is pivotally supported.

The T-coupling 34 has its lateral branch which is connected to one of the rear uprights of the frame, plugged, as indicated by the numeral 55 and the outer end of the longitudinal branch of the said coupling is preferably reduced, having screwed therein the horizontal branch 56 of a steam conducting pipe. The vertical and depending branch 57 of the said steam conducting pipe has its passage controlled by a hand operated valve 58, and has also connected thereto a gauge 59, whereby the amount of steam between the said pipe and the drum can be ascertained. The branch 57 has its lower end connected by a suitable coupling to a horizontally disposed transversely arranged pipe 60, the latter being made up of sections connected together by a T 61 in which is screwed a short pipe 62 that is likewise screwed in the generator tank adjacent to the top thereof. To

the outer end of the pipe 69 there is secured by a suitable coupling a vertical branch 63 whose passage is controlled by a hand operated valve 64 and which has at its end a funnel 65 that provides a filler spout for water to the steam generator chamber 15. Also connected to the said end of the tank 15 there are the spaced short pipes 64' of a tubular gauge 65', the couplings between the 10 short pipes and the gauge having their passages controlled by valves 66 and 67, the lower valve casing being also provided with a drain cock 68 whereby water from the generator tank 15 may find an outlet, when desired. The inner end of the horizontal branch of the T 34 is threaded and has screwed therein a nipple 69. Screwed in the nipple 69 there is a tube 70. Arranged to surround the tube and to cover the open 20 inner end thereof there is a fabric element 71. Arranged over the portion of the element 71 received on the tube 70 there is a sleeve 72, and arranged over the sleeve 72 there is a second tubular sleeve 73, which latter is received through an inwardly directed annular flange 74 that surrounds a central opening in the end of the drum. By this arrangement a suitable journal is provided for this 25 end of the drum, and also by this arrangement it will be seen that steam from the generating chamber passing through the closed end of the tubular fabric member 71 will be partly dry before entering the drum, the heat from the steam and the coil 36 further 30 drying the steam, so that the said steam, when directed against the cloth to be sponged, in a manner to be presently set forth, will be delivered in a practically dry state to permit of the cloth being sponged 35 and shrunk in an easy and expeditious manner and without liability of danger to the fabric thereof.

The drum 37 has its body portion apertured, as at 75, the said apertures being arranged in series throughout the length and circumference of the said drum, and arranged over the drum to close the apertures there is a tubular fabric sheet 77.

The operation of the device may be briefly described as follows:

The cloth to be sponged is arranged in folds or rolls on the table as indicated by the dotted lines in Figure 3 of the drawings and the shelf 11 is swung to horizontal 55 position as also shown by the dotted lines in the said figure. The cloth is directed around the roller 9 and from thence directed over the drum. Steam is let into the drum through the pipe 56, and as previously stated 60 enters the drum in a practically dry condition. Steam is also admitted into the coil. The crank handle is turned to slowly revolve the drum, and the portion of the cloth passing thereover is permitted to fold itself upon 65 a clean sheet of paper resting on the floor.

Should too much steam enter the drum the safety valve will be unseated, and the cock 38 is opened from time to time to allow condensation to escape from the coil to the atmosphere, while the valve 58 is actuated to 70 control the passage of steam from the generator into the drum. When short pieces or remnants of cloth are to be sponged, the same is wound around the drum and steam is let into the drum and into the coil in a manner 75 as just described. One end of the cloth is grasped by the hand of the operator and the cloth is slowly unwound from the drum.

It will be noted that I have provided a simple, efficient and effective apparatus for 80 sponging cloth for tailors' use in an expeditious manner, and while I have illustrated a satisfactory embodiment of my improved device, my features of invention are capable of extended application, and I do not wish 85 to be limited to the specific structure shown and described.

Having described the invention, I claim:—

1. In a cloth sponging apparatus, a table, a drop shelf for the top thereof and means 90 for holding the shelf in alignment with the top, a tank removably supported on the table frame below the top thereof, means for admitting water into the tank, means for indicating the level of water in the tank, means 95 for draining the tank, gas burners including spaced apertured tubes supported by the frame below the tank for heating the water therein to generate steam, a hollow drum supported by the table frame above the top 100 thereof, said drum having series of peripheral apertures and a fabric facing arranged thereover, a roller journaled on the frame below the drum over which cloth supported on the table top is guided to arrange 105 the same over the drum, means admitting steam generated in the tank into the drum, a filtering medium at the steam inlet in the drum, means regulating the pressure of steam in its passage to the drum, means in the drum 110 receiving steam generated in the tank for drying the steam in its passage through the apertures of the drum, and means for revolving the drum.

2. In a cloth sponging apparatus, a water 115 receiving tank and means for generating steam therein, an apertured drum having a fabric facing around which cloth to be sponged is arranged, means admitting steam from the tank through one end of the drum 120 and providing a journal for the said end of the drum, a filtering medium for the hollow journal, a coiled tube in the drum having a straight end extending through the second end of the drum, a bearing for said end, the 125 opposite end of the tube passing through the first mentioned end of the drum, a cock secured thereon, means for admitting steam from the tank into the coil to heat the same and dry the steam in the drum in its passage 130

through the apertures thereof, means for regulating the admission of steam to the coil, a blow-off valve associated with the steam admitting means for the coil, and means for revolving the drum.

3. In a cloth sponging apparatus, a table, a tank removably supported below the top thereof, means for admitting water into the tank, means for determining the level of water in the tank, a drain outlet for the tank, a burner below the tank for generating steam therein, a roller journaled in bearings adjustable on the table frame above the top thereof, a closed drum having an apertured periphery and a fabric facing arranged above the roller, a journal for one end of the drum supported by one of the table frame members including a pipe, a fabric tube having a closed outer end surrounding the pipe, and means surrounding the fabric tube for binding the same on the pipe, a valved pipe connection between said journal and generator tank, a gauge associated with said pipe, a coiled pipe

arranged longitudinally in the drum having one end extending therethrough, a cock secured to said end, the second end of the pipe being straight and journaled through one of the table frame members, a bushing on the outer end of the pipe, a flanged sleeve 30 screwed on said pipe contacting the bushing to force the latter in frictional engagement with the former, a valved pipe providing a steam passage from the tank to the drum, a cock having its casing secured to said pipe 35 and having a conical core secured to the bushing, said core having an annular series of apertures in a line with the bore of the casing and communicating with the bore of the core, a handle secured to the core, a 40 spring influenced safety valve connected to the cock casing, and the table designed to receive cloth to be sponged when the latter is guided over the roller and around the drum and the latter is turned by the handle 45 of the cock core.

In testimony whereof I affix my signature.
SAMUEL FISHER.
